UNITED STATES PATENT OFFICE

ALFRED B. FOWLER, OF BEVERLY, MASSACHUSETTS, ASSIGNOR TO UNITED SHOE MACHINERY CORPORATION, OF PATERSON, NEW JERSEY, A CORPORATION OF NEW JERSEY

ABRADING MACHINE

Application filed March 25, 1925. Serial No. 18,292.

This invention relates to work holders for abrading machines and is herein illustrated as embodied in a machine for grinding blades of rotary cutters as, for instance, those of heel trimming machines. The type of heel trimming blade disclosed for illustrative purposes is that commonly known as the Ultima blade. Such a blade, which is designed for use in machines of the type of the well known Ultima heel trimming machine, is curved both laterally and longitudinally and has a cutting edge profile which may vary from a slight curve for operation on heels with substantially straight sides to an ogee curve for operation on Louis and similar heels having variously curved sides.

In view of the foregoing, it is an object of the invention to provide an improved holder for use in an abrading machine and adapted for holding the blades of heel trimming cutters, such as blades of the type referred to, which holder will be constructed and arranged to allow the blades to be conveniently inserted therein and removed therefrom.

With this object in view, a feature of the invention consists in the provision, in an abrading machine, of a novel work holder having a plurality of co-operating clamping members for holding a blade, automatic means for securing an initial yielding clamping of the blade by said clamping members and manual means for securing an increased final non-yielding clamping action of the clamping arms on the blade. Thus, as illustrated, provision is made for separation of the clamping members, which are provided on their opposite interior faces with grooves that correspond to the opposite side edges of the blade being operated upon, this separation allowing the insertion of a blade between them in the grooves, after which one of the clamping members is automatically moved in the direction of the other to grip the side edges of the inserted blade and, upon manipulation of the manual means referred to, final firm clamping of the blade is effected.

It will be understood that the invention which is herein illustrated as being embodied

in a machine for supporting a cutter blade of the well-known Ultima type is in no respect limited to the particular type of blade to be operated upon other than may be determined from the scope of the appended claims.

The invention is more fully described in the following specification and shown in the accompanying drawings, in which

Fig. 1 is a top plan view of the grinding machine constructed in accordance with the present invention and shows the work carrier mounted on the slide bar and supporting the Ultima heel trimming blade;

Fig. 2 is a view in side elevation of the mechanism shown in Fig. 1; and

Fig. 3 is a detail, front elevational view of the work carrier with parts broken away to show the manner in which the carrier is connected with the slide bar.

Fig. 4 is a rear perspective view of the work holder with certain parts broken away;

Fig. 5 is a detail view showing the manner in which the work holder is mounted; and

Fig. 6 is a perspective view of an Ultima heel trimming blade.

Referring to the drawings, a work holder for supporting a heel trimming blade 36 is indicated generally at 22 and comprises a body portion 24 and a plurality of outwardly extending arms 40, 48 carried by the body portion and arranged to grip the opposite side edges of the blade 36. One of these arms, indicated at 40 is formed integrally with the body portion 24, and the other, indicated at 48, is provided with a lug 51 (Fig. 4) which fits into a groove 50 formed in a lateral extension of the body portion. The opposite interior faces of the clamping arms 40, 48 are provided with grooves 52 shaped to correspond to, and to receive, ridges formed on the side edges of the blade 36.

The provision of the lug 51 and the groove 50 permits the arm 48 to be slidably adjusted along the body member 24 toward or away from the rigid, integral arm 40 to facilitate positioning the cutting blade 36 within the holder and to accommodate readily blades of different widths. To the end of effecting this adjustment between the clamping arms, mechanism is provided which includes a sleeve 54

extending through the upper portion of the arm 40 and arranged for lengthwise movement relatively to the arm 40 but held against rotation by means of a fixedly carried key 77 (Fig. 4) engaging within a guideway 79 formed in the cylindrical surface of the sleeve 54. A screw rod 62 is rotatably mounted within the sleeve 54 and has one of its ends provided with an operating handle 64, and its opposite end is threaded at 66 for engagement within a correspondingly threaded bore 68 formed in the arm 48. A collar 70 is pinned to the screw rod 62 and co-operates with the handle 64 to prevent lengthwise movement of the rod relatively to the encompassing sleeve 54. Thus it will be seen that the rod 62 may be rotated, by means of the operating handle 64, in one direction to cause relative approach between the arms 40, 48, or, in the other direction to cause relative separation between the arms. Then also, the sleeve 54, carrying with it the rod 62, may be moved lengthwise to effect approach or separation between the arms 40, 48. The rod 62 thus serves as a slidably mounted connection to move the clamping member 48.

The work holder 22 is, however, provided with means which normally tends to move the slidable arm 48 in a direction towards the fixed arm 40, and is additionally provided with means tending positively and normally to prevent movement of the slidable arm 48 in a direction away from the fixed arm 40. Accordingly, a compression spring 72 is arranged to encircle the sleeve 54 and to extend between the upper portion of the arm 40 and the operating handle 64; thereby tending to move the operating handle to the left of the position illustrated in Fig. 1. Any movement of the handle 64 in this direction is imparted directly to the sleeve 54, the rod 62, and arm 48, causing the latter to approach the fixed arm 40.

The means for positively preventing movement of the arm 48 in the opposite direction (away from the arm 40) constitutes the sleeve 54 provided with a series of rack teeth 56 which are adapted to be engaged by a locking pawl 53 carried by a leaf spring 60 secured to the body portion 24. The teeth 56 are of a shape, as illustrated in Fig. 1, that when engaged by the pawl 53 relative approach between the clamping arms 40, 48, is permitted, but relative separation therebetween is prevented. In the use of the work holder, the leaf spring 60 is manually pulled back to retract the pawl 53 from engagement with the rack teeth 56, and the operating handle 64 is manually moved to the right of the position shown in Fig. 1, to separate the clamping arms 40, 48. With the arms 40, 48 so held, the leaf spring 60 is released, the blade 36 is inserted into the holder and the operating handle is next released to allow the compression spring 72 to expand, thereby

moving the arm 48 in the direction of the arm 40 until the opposite side edges of the blade 36 are engaged by the grooves 52 formed in the arms. Such an operation effects an initial adjustment of the arms relatively to the blade 36, and in order to apply further clamping pressure to the side edges of the blade and to effect a more accurate adjustment of the arms 40, 48 to the width of the supported blade, the handle 64 may be rotated to impart rotation to the screw rod 62, which movement causes the arm 48 to move slowly and positively, towards the arm 40. Such a provision allows a very minute and accurate adjustment of the blade-supporting members to be made.

A compression spring 80 encircles the threaded end of the screw-rod 62 and is for the purpose of preventing back-lash between the threads formed on the end of the rod 62 and those formed in the bore 68 of the arm 48.

The illustrated work-holder 22 is provided with gaging means to assist in positioning a cutter blade within the holder preparatory to performing an abrading operation upon the blade, or to assist in positioning successive blades with their cutting edges occupying substantially the same position relatively to a grinding wheel 12. To this end, the downwardly extending fixed arm 40 of the holder has an arcuate slot 42 formed therein anywhere lengthwise of which may be fixedly secured in a position of desired adjustment a stop 44 provided with a co-operating lock nut 46. A gage, herein illustrated as a finger 74, is pivotally secured to a projecting portion 38 of the arm 40 and is normally held in the in-operative position best illustrated in Figs. 1 and 4, by means of a torsion spring 78. The finger 74, however, may be manually moved into the position illustrated in dotted lines in Fig. 2, in which it lies above the groove 52 formed in the arm 40 and engages the cutting edge of the blade 36. Thus the blade may be inserted into the holder and moved up through the grooves into engagement with the gage 74, in which position the blade may be firmly held by means of the adjustable stop 44 cooperating with the clamping arms 40, 48.

The work holder 22 is mounted upon one extremity of a slide rod 20 (Fig. 1) in such a manner that it may be pivotally adjusted relatively to the rod for the purpose of varying the angle of presentation of the cutter blade 36 to the grinding wheel 12 to produce a cutting edge having a desired predetermined angular bevel. As illustrated in Figs. 2, 3, 4 and 5 the mounting of the work holder which permits of such an adjustment comprises a flat downwardly extending arm 32 formed on one end of the slide rod 20 and a shoulder bolt 26 (Fig. 3) which extends through the rod 20 and has threaded engagement with the body portion 24 of the work

holder. The shoulder formed on the bolt 26 is of such a height as to prevent binding frictional engagement between the rod 20 and body portion 24, and of such a diameter as to be capable of rotating freely pivotally within the bore formed in the rod 20; thereby permitting the work holder 22 to be pivotally swung relatively to the rod 20. Provision is made for locking the work holder in a desired position of adjustment relatively to the rod 20, and accordingly, the depending arm 32 of the rod 20 has formed therein an ar- 10 cuate slot 30. A locking bolt 28 (Figs. 3 and 5) extends through the slot 30 and through the body portion 24 of the work holder and is provided with a threaded extremity for receiving a co-operating locking nut 34. In adjusting the work holder, the nut 34 may be loosened, the holder swung into a desired po- 15 sition and the nut 34 tightened to secure the holder in the adjusted position.

Inasmuch as the illustrated grinding wheel 12, which is mounted for rotation on a shaft 10, is of discal shape (Fig. 1), and is of a width considerably less than that of the cutter blade 36, it will be appreciated that in order to grind effectively completely along the length of the cutting edge, the supported blade must be traversed across the peripheral portion of the grinding wheel, or, on the other hand, the grinding wheel must be traversed along the cutting edge of the supported blade. In the illustrated embodiment, the grinding wheel 12 is mounted for rotation only, being held against bodily displacement, and the work holder 22 is adapted to be traversed relatively to the wheel. Accordingly, the slide rod 20, to which the work holder is secured, is mounted within a sleeve 18 formed at one extremity of a reciprocable slide bar 16 (Fig. 1). A bearing 14 is provided for supporting the slide bar 16 and for guiding the latter during its reciprocation.

Further, since the illustrated cutter blade is curved both laterally and longitudinally, it is essential to properly grinding the blade that it be moved gradually towards the grinding wheel 12 during the early part of the traversing movement, and gradually away from the wheel during the later part of the movement, thereby insuring that the entire length of the cutting edge will be ground, notwithstanding the general concavity of the blade. To this end, as illustrated, the slide rod 20 is provided with a bolt 92 which extends upwardly through a slot 94 formed in the sleeve 18. A link 86 pivoted between its ends to a rigid extension 88 of the sleeve 18 is arranged at one end closely to surround the bolt 92 and at its opposite end is provided with a follower roll 84 for engaging a template 82. A compression spring 90 tends to hold the roll 84 in engagement with the template 82 which is fixedly secured to the bearing member 14 in any suitable manner.

By forming the template in accordance with the concavity of the blade to be ground, it will be appreciated that during movement of the work holder across the face of the grinding wheel 12, the follower roll 84 will ride over the irregular surface formed on the template, thereby swinging the link 86 about the arm 88 and causing the slide rod 20 to move toward and away from the grinding wheel, which movement is, of course, im- 70 parted to the work holder 22 and the sup- 75 ported blade 36.

The machine as illustrated is provided with means which may be operated either automatically or manually for feeding the work holder 22 and the parts which support the holder toward or away from the grinding wheel 12 in order properly to position the supported blade at the commencement of a grinding operation or to feed the blade toward the grinding wheel as the former is worn away during the course of the grinding operation. To this end a screw shaft 15 is threaded into the bearing 14 in such a manner that rotation of the screw shaft imparts 80 bodily movement to the bearing 14, the slide bar 16, and the parts carried thereby. The feeding mechanism of which the shaft 15 is a part, is not claimed herein, being set forth and claimed in my copending application 85 Serial No. 22,144, filed April 10, 1925.

Although the device as illustrated is for the purpose of supporting an Ultima heel trimming blade, it will, of course, be understood that various forms of work carriers may 100 be interchangeably mounted on the supporting rod 212 to accommodate blades of all forms, without in any respect departing from the scope of my invention.

Having thus described the invention, what I claim as new and desire to secure by Letters 105 Patent of the United States is:—

1. In an abrading machine, a work holder comprising a body portion having a clamp- 110 ing arm formed integral therewith, a co- operating clamping arm mounted for sliding movement relatively to the integral arm, means including a spring, a rack bar, and a locking pawl for adjusting initially said clamping arms relatively to each other, and means including a screw-threaded rod for effecting a final adjustment of said clamping arms.

2. In an abrading machine, a work holder comprising a body portion provided with an 120 integral clamping arm and a slidably mounted clamping arm, a sleeve, having rack teeth formed thereon, extending through the integral arm in the direction of the slid- 125 able arm, a rod extending through said sleeve and having threaded engagement with said slid- able arm, means to prevent rotation of said sleeve, means to prevent longitudinal move- ment of said screw rod relatively to said sleeve, a spring arranged to encompass a 130

portion of the sleeve and to urge said sleeve in a direction to cause approach between said slidable arm and said integral arm, and a locking pawl carried by said body portion for co-operation with said rack teeth in holding the sleeve against movement in a direction to cause separation between the slidable arm and the integral arm.

3. In an abrading machine, a work holder comprising a plurality of clamping arms provided with portions having curved grooves and constructed and arranged to engage and support a curved knife, automatic means constructed and arranged to secure an initial yielding clamping of the knife by said clamping arms, and manual means constructed and arranged to secure an increased final non-yielding clamping of the knife by the clamping arms.

20 In testimony whereof I have signed my name to this specification.

ALFRED B. FOWLER.
